Warren Allen,

BY

Richard Allen,

ATTORNEY

UNITED STATES PATENT OFFICE.

WARREN ALLEN, OF DANSVILLE, NEW YORK.

REPAIR-PEG.

1,292,984.

Specification of Letters Patent.

Patented Feb. 4, 1919.

Application filed January 11, 1918. Serial No. 211,390.

To all whom it may concern:

Be it known that I, WARREN ALLEN, a citizen of the United States, residing at Dansville, in the county of Livingston and 5 State of New York, have invented certain new and useful Improvements in Repair-Pegs, of which the following is a specification.

This invention relates to an improvement 10 in pegs, and particularly to a repair peg for peg racks as used in shoe factories and the like.

An object of my invention is to provide 15 a peg and peg holder which may be used as a repair unit to replace the original pegs as mounted in the racks by the manufacturer, should the same become bent or worn, and which structure is of such character that it can be fitted in place and will hold securely 20 even though the peg opening has become quite materially enlarged or the wood has been split.

A further object lies in so shaping the receiving end of the peg that lasts will not be 25 damaged or split in the use of the peg, and to so construct the holder that if the peg becomes bent or broken it can be readily replaced, the structure of the holder being such that it is easily adapted to use in wooden or 30 metal pegs.

With the above and other objects in view, which will be in part described and in part understood from the specification, drawings, and claims, my invention consists in certain 35 novel features of construction and combination of parts which will be hereinafter more clearly set forth.

In the drawings:—

Figure 1 is a view taken in section through 40 a peg bar having my improved peg and holder mounted thereon;

Fig. 2 is a view in elevation of the bar with the repair peg fitted thereto;

Fig. 3 is a sectional view taken trans- 45 versely through a peg bar and through a holder fitted thereto;

Fig. 4 is a top plan view of the structure shown in Fig. 2;

Fig. 5 is a perspective view showing the 50 fastening plate of the holder; and,

Fig. 6 is a perspective view of the peg clamping portion as the same appears before being secured to the fastening plate.

As has been stated, the repair peg is adapt-

ed for use in conjunction with the peg bars 55 as already installed and in use, and the bar 1, as here shown, is of substantially standard form, as is also the peg 2, with the exception that this peg has the outer ends thereof rounded and made substantially ball-shaped as indicated at 3.

A fastening plate 4, which is substantially L-shaped when in cross section, has a peg receiving opening 5 formed through one of the arms closely adjacent the bend thereof, this 65 arm being fluted through to its end as indicated at 6. Countersunk openings 7 and 8 are provided in the ends of the two arms of this fastening plate 4 for reception of screws or other fastening means by which the plate 70 is mounted upon the bar 1. That arm of the fastening plate 4 which has the peg receiving opening 5 therein is also provided with rivet openings 9, which are oppositely disposed on each side of the fluted opening 6, and a rivet 75 opening 10 is provided in the remaining arm of the plate and adjacent the peg receiving opening 5.

A peg holding member, the formation of which is best disclosed in Fig. 6, is bent up 80 from a single piece of metal or formed from a casting, and comprises a sleeve 11 having ears 12 and 13 extending therefrom and provided with alined openings, one of which is screw-threaded. A wing 14 is extended 85 from the sleeve 11 at a point opposite to the extensions of the ears 12 and 13, and these ears 12 and 13 have wings 15 and 16 laterally disposed therefrom, the wings 15 and 16 having the inner sides thereof extending substantially at right angles to the inner side of the wing 14. The wing 14 has an opening 17 therethrough so located that as the sleeve 11 is lined up with the opening 5 of the fastening plate 4, this opening 17 will 95 register with the opening 10 of the plate, and a rivet 18 is clenched through these registering openings to mount the peg clamping member upon the fastening plate. Slotted openings 19 and 20 are provided in the wings 100 15 and 16, and rivets 21 and 22 are passed through these slotted openings and through the openings 9 of the fastening plate 4, the purpose in providing the slotted openings in these wings and including the fastening plate 105 as at 6, being to provide for expansion and contraction of the sleeve 11 as it is left free to open to its own resiliency or is drawn in

through the medium of the clamp screw 23 which is received through the alined openings of the ears 12 and 13.

It will of course be understood that the sleeve 11 will be given angular disposition with respect to the wings 14, 15, and 16, and consequently the fastening plate 4, which will cause the central opening thereof to be substantially parallel with the angular 10 position of the pegs in the bars of the peg rack which is to be repaired, and when a peg is broken out or the bar becomes so worn and split that a peg will not hold, the plate 4 will be fastened in place upon the bar at 15 the proper point by the use of screws or other suitable fastenings, and then the clamp screw 23 is loosened to allow for expansion of the sleeve 11, following which the peg 2 is fitted in place and adjusted to the proper 20 length. Now when tightening in on the clamp screw 23, the ears 12 and 13 are drawn together and in consequence the sleeve 11 is contracted around the peg 2 to clamp the same in rigid mounting.

25 From the foregoing it will be seen that I have provided a repair peg which is of such character that it is particularly adaptable for use in the connection as herein mentioned, but can also be used to advantage 30 in other connections; and, while I have in the foregoing, described a specific embodiment of the invention, it is to be understood that in practice, I do not limit myself to such specific detail but may resort to practical 35 modifications as to construction and arrangement of the parts, as well as materials, which may fall within the scope of the invention as defined in the appended claims.

Copies of this patent may be obtained for five cents each, by addressing the "Commissioner of Patents, Washington, D. C."

I claim:—

1. A repair peg for peg racks including 40 a substantially L-shaped fastening plate provided with openings for reception of fastenings by which the plate is secured upon one of the bars of the rack, said fastening plate having an opening therethrough for reception 45 of the peg, a slit sleeve having wings extending therefrom, fastenings passed through the fastening plate and through the wings of the sleeve to secure the sleeve upon the fastening plate and line the same up 50 with the opening thereof, and a clamp screw by which the sleeve is tightened.

2. A repair peg for peg racks including in combination with a peg, a fastening plate of substantially L-shaped form provided 55 with openings for fastenings by which the same is mounted upon the rack bars, said plate having a peg receiving opening therethrough, and also provided with rivet openings, a sleeve open at one side and having 60 ears extending at the open side, said ears having alined openings therethrough one of which is screw-threaded, wings extending from the sleeve and from the ears, rivets received through the wings and through the 65 rivet openings of the fastening plate, and a clamp screw received through the alined openings of the ears.

In testimony whereof I affix my signature in presence of two witnesses.

WARREN ALLEN.
